United States Patent

Des. 241,011
Patented Aug. 17, 1976

241,011

JAR OR SIMILAR ARTICLE

Floyd E. Pettengill, Lancaster, Ohio, assignor to Green Bay Food Company, Green Bay, Wis.

Filed May 1, 1974, Ser. No. 465,879

Term of patent 14 years

Int. Cl. D9—01

U.S. Cl. D9—141

FIG. 1 is a perspective view of a jar or similar article showing my new design;

FIG. 2 is an elevational view thereof;

FIG. 3 is a top view thereof; and

FIG. 4 is a bottom view thereof.

I claim:

The ornamental design for a jar or similar article, substantially as shown and described.
